CLAIM

The ornamental design for a pet harness safety system, as shown and described.

DESCRIPTION

FIG. 1 is a perspective view of a pet harness safety system of the claimed invention, shown in use;

FIG. 2 is an exterior view of the pet harness safety system shown unfolded for clarity;

FIG. 3 is an interior view thereof;

FIG. 4 is an enlarged perspective view of the back plate of the pet harness safety system shown in an open position for clarity; and,

FIG. 5 is an enlarged perspective view of the back plate of the pet harness safety system shown in a closed position for clarity.

The broken line showing of a dog in FIG. 1 is environmental and not claimed.

The strap in FIG. 1 is shown broken away for ease of illustration.
